CLAIM

The ornamental design for a mid-section separable and nestable bottle, as shown and described.

DESCRIPTION

FIG 1 is an exploded, top, perspective view of a mid-section separable and nestable bottle showing my new design;
FIG. 2 is a left side view thereof;
FIG. 3 is a front side view thereof;
FIG. 4 is a right side view thereof;
FIG. 5 is a back side view thereof;
FIG. 6 is a top view thereof;
FIG. 7 is a bottom view thereof;
FIG. 8 is a left view with the bottle sections snapped together and securely nested thereof;
FIG. 9 is a bottom perspective view with the bottle sections snapped together and securely nested thereof;
FIG. 10 is sectional view taken along lines 10-10 from FIG. 3 thereof, and,
FIG. 11 is a sectional view taken along lines 11-11 from FIG. 8.
